(57) **CLAIM**

The ornamental design for a mouthpiece for electronic cigarette, as shown and described.

DESCRIPTION

FIG. 1 is a perspective view of a mouthpiece for electronic cigarette showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is the other perspective view of mouthpiece for electronic cigarette;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines shown in FIGS. 1, 2, 7 and 13 depict parts of the mouthpiece for electronic cigarette that form no part of the claimed design; the broken lines in FIGS. 8-12 and 14 shown as the electronic cigarette are directed to environment and forms no part thereof.
